(57) **CLAIM**

The ornamental design for a bottle, as shown and described.

DESCRIPTION

FIG. 1 is a perspective view of an embodiment of a bottle embodying our new design;

FIG. 2 is a front view thereof;

FIG. 3 is a left view thereof;

FIG. 4 is a back view thereof;

FIG. 5 is a right view thereof;

FIG. 6 is a top view thereof;

FIG. 7 is a bottom view thereof;

FIG. 8 is a perspective view of an embodiment of a bottle embodying our new design;

FIG. 9 is a front view thereof;

FIG. 10 is a left view thereof;

FIG. 11 is a back view thereof;

FIG. 12 is a right view thereof;

FIG. 13 is a top view thereof;

FIG. 14 is a bottom view thereof;

FIG. 15 is a perspective view of an embodiment of a bottle embodying our new design;

FIG. 16 is a front view thereof;

FIG. 17 is a left view thereof;

FIG. 18 is a back view thereof;

FIG. 19 is a right view thereof;

FIG. 20 is a top view thereof; and,

FIG. 21 is a bottom view thereof.

The broken lines in the drawings illustrate the portions of the bottle that form no part of the claimed design. Certain features currently not in broken lines may be placed into broken lines in other embodiments while other features in broken lines may be placed in solid lines in other embodiments.

1 Claim, 12 Drawing Sheets
